pany, permanent trustee

Application April 1, 1932, Serial No. 602,482

23 Claims. (Cl. 101—394)

This invention relates in general to type forms or chases employed in clamping type bodies together, having for its main object the provision of a device of the kind described of a simplified, 5 more efficient design and construction that will effect a substantial saving in time and labor in securing type bodies within the chase.

Another object is to provide a chase with novel simplified means for operatively binding or locking type bodies within the said chase.

A further object is to provide a chase adapted to be operated by the application of a single means for binding or locking the type bodies therein preparatory to printing therefrom.

15 It is also an object of the invention to provide a type form or chase of generally improved construction, whereby the device will be simple, durable and inexpensive in construction, as well as convenient, practical, serviceable and efficient in 20 its use.

Figure 1 is a top plan view of an embodiment of the invention;

Figure 2 is an enlarged, fragmentary sectional detail view of parts taken on line 2 of Figure 1; 25 Figure 3 is an enlarged, fragmentary sectional view taken on line 3 of Figure 1;

Figure 4 is a fragmentary plan view of details employed in a modified form of the invention, showing a locking or clamping position of the quoins;

Figure 5 is a fragmentary plan view of the device illustrated in Figure 4, showing a different position of the quoins and coacting parts;

Figure 6 is an enlarged, fragmentary elevational view, partly in section taken on line 6 of Figure 4, illustrating the link or toggle-joint construction employed in the embodiment shown in Figures 4, 5; and

Figure 7 is an enlarged, fragmentary elevational view, partly in section taken on line 7 of Figure 4.

For the purpose of illustrating the invention we have shown in the accompanying drawings two forms thereof which are at present preferred by us, since the same have been found in practice to give satisfactory and reliable results, although it is to be understood that the various instrumentalities of which our invention consists can be variously arranged and organized and that the invention is not limited to the precise arrangement and organization of the instrumentalities as herein shown and described.

With more particular reference to the drawings wherein similar characters of reference indicate corresponding parts in the preferred forms

of the invention, 11 designates a frame within which a pair of slidable or adjustable members or quoins 12, 13 are operatively arranged. On the reduced end 14 of the quoin 12 a pair of links 15 are pivotally secured by a pin 16 fastened thereto. The links 15 are hingedly connected to two other pairs of links 17 and 18 respectively, by means of a pin 19 secured thereto as best shown in Figure 2, a washer 21 maintaining said last mentioned pair of links 17 in spaced relation. The 10 assembly of links and coacting details above described form substantially a toggle-joint construction for operating the quoins of the device as will hereinafter appear.

The links 18 are pivoted to projecting pins or 15 trunnions 22 of a small block or nut 23 having a hole 24 through which the reduced threaded stem 25 of an adjusting screw 26 is passed, the said block 23 being secured to the threaded stem 25 by the nuts 27, 28. The body portion 29 of the adjusting screw 26 is threadedly engaged in a hole 31 formed in the frame 11 and has an angular head 32 adapted to be received in a socket wrench or key (not shown) for moving the quoins 12, 13 in the normal operation of the device.

The quoins 12, 13 as clearly shown in Figure 1, are each provided with a plurality of inclined surfaces 33, which are adapted to slidably coact with corresponding inclined surfaces 34, formed on a pair of bars 35, 36 which may be considered as a component part of the quoins 12, 13 and which directly engage the type forms (not shown) within the interior of the frame 11. When the angular head 32 of the adjusting screw 26 is engaged by a socket wrench or other suitable means, the turning of the said screw 26 in a clockwise direction will advance the block 23 and links 18 towards the center of the frame 11, thereby angling the other links 15, 17 into alignment or parallelism and, consequently, sliding the outer members 12, 13 of the quoins longitudinally along the side and bottom bars 35, 36 of the frame 11. This sliding of the outer member or locking bars of the quoins 12, 13 will cause the inclined or wedge surfaces 33 to engage with the coacting 30 surfaces 34 on the inner members or type-engaging bars 35, 36, commonly referred to as side and bottom sticks. The said side and bottom sticks will now move inwardly as the wedge surfaces 33, 34 ride over one another, and thus 35 clampingly engage the type forms to lock same within the frame 11. The unlocking of the quoins is accomplished by merely turning the key in a counter-clockwise direction which results in sliding the quoins 12, 13 so as to permit the side and 40

wedge surface 33 to engage with the coacting 45 wedge surface 34 on the inner members or type-engaging bars 35, 36, commonly referred to as side and bottom sticks. The said side and bottom sticks will now move inwardly as the wedge surfaces 33, 34 ride over one another, and thus 50 clampingly engage the type forms to lock same within the frame 11. The unlocking of the quoins is accomplished by merely turning the key in a counter-clockwise direction which results in sliding the quoins 12, 13 so as to permit the side and 55

bottom to move outwardly, thus unclamping the type bodies.

In the modified form of the invention shown in Figures 4 to 7 inclusive, 37 designates a frame, 5 shown fragmentarily, within which adjustable or slidable quoins 38, 39 are secured, each of the quoins 38, 39 having threadedly secured thereto a guide pin 41 which is slidably confined in a hole or passageway 42 formed in the frame 37, 10 whereby the quoins 38, 39 may be slidably retained against the adjacent side or bottom bars of the frame.

The means employed in the present form of the invention for operatively connecting the 15 quoins together so that both may be actuated by a single instrumentality, which may be a socket wrench or other suitable implement, comprises a pair of links 43 pivotally joined at one end by a pin 44 to the quoin 39, the other end of the 20 said links 43 being hinged by a pin 45 to one end of a link 46 and a pair of links 47.

The other end of the pair of links 46 is hingedly connected by a pin 48 to the quoin 38, while the other ends of the links 47 are hingedly connected 25 by a pin 49 to a pair of links 51 pivotally secured by a pin 52 to a link 53. The links 51, at one end, are formed with a small shoulder or cam 51' which, as best shown in Figure 4 serves to maintain the links 43, 46 in normal locked position 30 and, consequently, the type-engaging bars hereinafter mentioned in clamping engagement with the type forms. The links 47 and 51 which are hinged together as at 49 constitute what might be considered a second toggle joint or equalizing 35 device for applying pressure to the first toggle joint defined by the links 43 and 46 connected by the hinge or pin 45. The last mentioned link 53 is formed with an enlarged portion 54 or block serving as a plunger head and having a pin 55 40 secured thereto, the ends of which latter ride in a slot 56 formed in the frame 11. A spring 57 secured in a pocket 58 is engaged against the enlarged portion 54 of the link or plate 53 and maintains pressure on the plunger head or block 45 55 tending to maintain the quoins 38, 39 yieldingly in the position shown in Figure 4.

The quoins 38, 39 have inclined or wedge surfaces 59 which are coactingly engaged against corresponding wedge surfaces 61 formed on the 50 type-engaging bars or side and bottom sticks 62, 62' respectively, each of which may be considered as a component part of the adjacent quoin 38, 39, so that when the quoins 38, 39 are slid in the frame by means hereinafter described, the coacting wedge surfaces 59 and 61 will serve to thrust inwardly the type-engaging bars 62 to clamp the type forms.

By inspection of Figures 4 and 5 it will be seen the link 47 is notched as at 63 and provided with 60 small flanges or wings as at 64 in order to permit the application of a suitable key or wrench (not shown) to the said link 47 to turn or shift same in order to move the links 43, 46 into the positions approximately indicated in Figures 4 and 65 5 for shifting the quoins 38, 39 to move inwardly the type-engaging bars 62 for locking and unlocking the type forms within the frame 37. The spring 57 which serves to take up lost motion in the link or toggle-joint system illustrated, may 70 be regulated by a screw 65 threaded in an enlarged portion of the passageway 58 in order to maintain the desired degree of pressure against the flange head 54 and on the toggle-joint system connected therewith. The movement of the 75

plunger head 54, it will be observed, is restricted to the length of the small slot 56.

We are aware that the invention may be embodied in other specific forms without departing from the spirit or essential attributes thereof, 5 and we therefore desire the present embodiment to be considered in all respects as illustrative and not restrictive, reference being had to the appended claims rather than to the foregoing description to indicate the scope of the invention. 10

What we claim is:

1. In a device of the kind described, the combination of a frame, a plurality of coacting quoins arranged on adjacent sides of said frame and a single manually operable toggle joint for moving 15 said plurality of coacting quoins into operative and inoperative positions, said toggle joint being resiliently biased.

2. In a device of the kind described, the combination of a frame, quoins arranged in angular 20 relation and slidably mounted in said frame, said quoins being coactingly joined to a single-joint, wedge means on said quoins and on coacting bars engaged therewith, whereby when said toggle-joint is actuated said bars may be moved to type-locking and type-unlocking positions, and spring means for biasing the toggle joint and consequently the quoins in the said type-locking position. 25

3. In a chase of the kind described, the combination of a pair of quoins arranged in angular 30 relation, each quoin being composed of two members having coacting wedge surfaces arranged thereon, and a single manually operable toggle-joint for sliding one member of each pair of said 35 quoins to thrust inwardly and outwardly the other member of each of said pair of quoins for type-locking and type-unlocking positions, said means being resiliently pressed. 30

4. In a chase of the character described, a 40 frame, a pair of quoins movably mounted in said frame and interconnected by a toggle-joint, resilient means for maintaining said toggle-joint and quoins in locked position for securing type forms therein, and a single manually-operable 45 means for actuating said toggle-joint.

5. In a chase of the character described, a frame, a pair of quoin members slidably mounted within said frame and joined by a manually-operable toggle-joint, wedge surfaces on said quoin 50 members and engaged with registering wedge surfaces on a pair of coacting members directly engageable with type forms for locking and unlocking same within the frame when said first mentioned pair of quoin members are actuated 55 by said toggle-joint, said toggle joint being resiliently biased by a spring.

6. In a chase of the kind described, the combination of a pair of quoin members having wedge 60 surfaces engaged with registering surfaces secured to a second pair of coacting quoin members, a plurality of links operatively connecting said first-mentioned pair of quoin members, and means secured to at least one of said links for operatively maintaining said links in position to effect a 65 locking and unlocking of said quoins for engaging type forms, and other means for taking up lost motion in said links and quoins.

7. In a chase of the character described, a frame, a pair of quoin members slidably mounted 70 in said frame and joined to a plurality of links including a toggle-joint, one of said links serving to normally maintain said toggle-joint in position for locking said quoins in operative position for clamping type forms, a second of said links 75

being manually-operable for actuating all of said links and adjustable yielding means for taking up lost motion in said plurality of links.

8. In a device of the kind described, the combination of a frame, quoins slidably mounted in said frame, side and bottom sticks coactingly engaged with said quoins, a manually-operable toggle-joint joined to said quoins for actuating same and said side and bottom sticks in operative and inoperative positions, means for maintaining said toggle-joint in position for retaining said side and bottom sticks clampingly engaged with type forms receivable in said frame, and other means including an adjustable spring for maintaining a resilient bias on said toggle joint.

9. In a device of the kind described, the combination of a frame, quoins movably mounted in said frame and joined by means secured to a manually-operable member secured in the frame, whereby when said manually-operable member is actuated, said means will be moved to cause said quoins to clampingly engage type forms, said manually operable member including an adjustable resilient means for maintaining a pressure upon said member.

10. In a device of the kind described, the combination of a frame, quoins movably mounted in said frame and joined by link means, and a manually-operable member connected to said quoins and mounted in said frame for operating said link means and quoins, said link means being resiliently biased.

11. In a device of the kind described, the combination of a frame, a pair of quoins members slidably mounted in the frame, and a toggle-joint secured to the quoins and hingedly connected to means mounted in the frame for adjusting said quoins, said means being resiliently biased.

12. In a chase adapted to receive a printing form, quoins operable to exert clamping pressure on adjacent sides of the form, a single means for operating the said quoins, and an equalizing device interposed between the said means and the quoins, said equalizing device being spring pressed.

13. In a chase adapted to receive a printing form, quoins operable to exert clamping pressure on adjacent sides of the form, a single means for operating the said quoins, and a toggle device interposed between the said means and the quoins, said device being resiliently biased.

14. In a chase of the character described, a frame, a pair of quoins movably mounted in said frame, a pair of cooperating toggle members one of which is hingedly connected to each of the quoins, a link pivotally connected to both toggle members, and other means hingedly connected to said link whereby the toggle members and consequently the quoins may be operated.

15. In a device of the kind described, the combination of a frame, a pair of quoins arranged on adjacent sides of said frame, a single manually operable toggle joint for actuating said quoins into operative and inoperative positions, and other means threadedly engaged in said frame for actuating said toggle joint.

16. In a chase of the character described a

frame, a pair of quoins members arranged in angular relation and slidably secured to said frame, said quoins members being interconnected by a toggle joint, said toggle joint being operable by a single means for moving said quoins into operative and inoperative positions, said means being threadedly engaged with the frame. 5

17. In a chase adapted to receive a printing form, quoins operable to exert clamping pressure on adjacent sides of the form, a toggle device 10 operable to simultaneously lock the said quoins, and means threaded in the frame for operating the toggle device.

18. In a printer's chase, a frame, a pair of quoins members slidable relatively to adjacent 15 sides of the frame, a toggle device operable to move the quoins members simultaneously and/or independently, an operating screw threaded into the frame, a swivel connection on the screw, and a member pivotally connected to the swivel and 20 to the toggle device.

19. In a printer's chase, a frame, a pair of quoins members slidable relatively to adjacent sides of the frame, a toggle device operable to move the quoins members simultaneously and/or 25 independently, an operating screw threaded into the frame and operable from the outside thereof, a swivel connection on the screw, and a member pivotally connected to the swivel and to the toggle device. 30

20. In a device of the kind described, the combination of a frame, a pair of quoins arranged on adjacent sides of said frame, and manually operable means including a toggle and screw for moving said quoins into clamped and into un- 35 clamped positions.

21. In a device of the kind described, the combination of a frame adapted to receive type forms, members arranged on adjacent sides of said frame and adapted to be engaged with and be 40 disengaged from said type forms, a toggle joint operatively connected to said members for adjusting same, and a threaded member for moving the first mentioned members into clamping and unclamping positions. 45

22. In a chase adapted to receive a printing form, a frame, slidably mounted bar-like members operable to exert clamping pressure on adjacent sides of the form, a single means secured to said frame for positively operating said members into and out of clamping position, and pressure equalizing means interposed between said single means and said members through which said single means acts to operate said members. 50

23. In a chase adapted to receive a printing 55 form, slidably mounted bar-like members operable to exert clamping pressure on adjacent sides of the form, a single means for actuating said members, connecting means between said single means and each of said members, and resilient 60 means adapted to act on said members, said single means, and said connecting means, to apply pressure to the said members in the direction in which they operate.
